BY Eugenie Ayres,

ATTORNEY.

UNITED STATES PATENT OFFICE.

EDWARD P. DEHLER, OF ST. JOSEPH, MISSOURI.

LEGGING.

1,132,835.

Specification of Letters Patent. Patented Mar. 23, 1915.

Application filed February 11, 1913. Serial No. 747,596.

To all whom it may concern:

Be it known that I, EDWARD P. DEHLER, a citizen of the United States of America, residing at St. Joseph, in the county of Buchanan and State of Missouri, have invented 5 certain new and useful Improvements in Leggings, of which the following is a specification.

The object of my invention is chiefly to 10 produce a lace and spring legging in which the use of hooks is entirely dispensed with, that secures a perfect fit to the leg and in which the liability of the lacing becoming loosened from hooks when traveling on foot 15 or horseback through the woods or brush is wholly obviated. These objects I secure by means of the construction shown in the accompanying drawings, in which,—

Figure 1 is a perspective of a legging 20 laced up and fitted to a leg; Fig. 2 is a perspective of such legging partly unlaced and open showing a broad tongue; Fig. 3 is an enlarged sectional perspective detail of a legging showing springs therein broken 25 away; Fig. 4 is a perspective of a spring showing the curve thereof, and Fig. 5 is a sectional detail of a spring with a punched hole therein forming an eyelet.

Similar letters refer to similar parts 30 throughout the several views, the letter A representing the legging canvas, B a boot or shoe and C a strap by which to buckle and hold the legging down.

D D are two metal strips forming flat 35 springs which are inserted in flap D' and fold D² of the canvas or other material. As shown in Fig. 4 these springs are curved thereby adapting them to the form of the calf of the leg and aiding in the legging 40 forming a perfect fit. Said springs are provided with punched holes d d with which perforations d' d² in the canvas flap and fold register to permit a lacing, E, to engage. These springs are somewhat shorter 45 than the flap and fold that receive them to obviate the lower ends of the springs punching or marring the wearer's shoes, and in place of the springs I substitute near the bottom of the opposite flap D' and fold D² 50 eyelets or gromets, e e.

It should be understood that the flap D' in the legging is not made from the selvage or edge of the canvas, but preferably by making a fold in the body of the canvas or other material and stitching it from top to 55 bottom at a width suited to the width of the spring: The tongue F, as shown in Fig. 2, is an extension of the same material and serves as a protection for the leg underneath the lacing at the meeting place of said flap 60 and fold. By the construction of said flap it is not only a fold in the canvas but is foldable backward and then forward thereby rendering it possible to easily use eyelets instead of hooks for lacing up the legging. The punched holes in said spring strips are clenched, as shown in Fig. 5, thereby preventing the rough or spread edge 65 of the punched holes cutting the lacing and rendering substitutes for eyelets. 70

H H are rivets which are inserted through the spring and canvas near the top and bottom of the legging to hold the punched holes in the spring in position to register with the perforations in the canvas. 75

I hereby reserve to myself the right to use eyelets, loops or rings in place of said punched holes and perforations and to make any other changes in manufacture 80 that are purely mechanical.

What I claim and desire to secure by Letters Patent, is,—

A legging comprising a legging body having an opening at one side throughout its entire length, the edge portion of said body 85 adjacent the front side of said opening forming a front flap and having a pocket extending longitudinally thereof throughout its length, the other edge portion of said body forming a tongue arranged to 90 lap behind said front flap for closing said opening, said body having a rear flap formed at the juncture of said tongue with said body and having a pocket extending longitudinally thereof throughout its 95 length, a metal stiffening strip in each of said pockets extending from the upper end of said body and terminating above the lower end thereof, rivets through the ends of said strips and through said flaps, each 100

of said flaps having a plurality of lacing apertures extending through the metal strip and through the material of the flap and a lacing aperture extending through 5 the material of the flap below the lower end of the metal strip, and a lace cord adapted to be laced through said lacing apertures.

In testimony whereof I affix my signature in presence of two witnesses.

EDWARD P. DEHLER.

Witnesses:

CHAS. A. JOHNSON,
F. M. LAWLOR.
